Attorneys.

UNITED STATES PATENT OFFICE.

JULIUS E. ULMER, OF DETROIT, MICHIGAN.

DRAFTING APPARATUS FOR ENLARGING OR REDUCING PICTURES.

SPECIFICATION forming part of Letters Patent No. 406,796, dated July 9, 1889.

Application filed December 13, 1888. Serial No. 293,500. (No model.)

To all whom it may concern:

Be it known that I, JULIUS E. ULMER, a citizen of the United States, residing at Detroit, county of Wayne, State of Michigan, have invented a certain new and useful Improvement in Drafting Apparatus for Enlarging and Reducing Pictures; and I declare the following to be a full, clear, and exact description of the invention, such as will enable others skilled in the art to which it pertains to make and use the same, reference being had to the accompanying drawings, which form a part of this specification.

In the drawings, Figure 1 is a perspective view of an apparatus illustrating my invention. Fig. 2 is a view of the frame with the drawing-board or stretching-frame removed. Fig. 3 represents the clamps used to hold the movable pointer-supports. Fig. 4 shows the mode of holding the reduced scale in place. Fig. 5 is an enlarged view of the movable pointer. Fig. 6 is a detail view of a section of the frame-work.

In carrying out my invention A represents a suitable frame; B, a drawing board or frame with a sheet of paper stretched upon it.

C represents the picture to be enlarged.

D is a pivoted bar. This pivot is located at d on the line of the edge of the bar. At d' 3c the bar is provided with an inch-scale, and which is permanently fixed to the bar, or preferably so. At d² is a reduced scale. This scale is made interchangeable with other scales of enlarged or diminished graduations, as the case may be, and is adjustable above the bar. At the free end of the bar D is a hook d³. To this may be engaged a ring or loop e at the end of a cord E, and at the other end of this cord is a suitable weight e'.

40 This is designed to counterpoise the weight of the bar, so that it will stand at any level. If at any time it is desirable to remove the bar D, the cord may be unhooked from the end of the bar and be engaged with a stationary hook or pin e² on the supporting-frame. The bar may then be removed from its pivot d, and the drawing-board or stretching-frame may likewise be removed.

45 F is a movable support carrying a piece of paper or card f, and held in place upon the bar D by suitable friction-clamps, preferably

springs f'. The card f has a point f² to assist in logging off the work, as will be hereinafter explained. G is another similar movable support carrying a piece of paper or card g, and with a similar point g².

I will now explain the operation of the device.

Suppose that I want to make a picture of a person, and I want the head to be, say, nine 60 inches long, and upon a field of, say, twenty by twenty-four inches in dimensions, and I want to copy from a picture in which the head is only three inches in length. I select or make a scale d² in which the graduations 65 corresponding with nine inches shall occupy only three inches in length, or in which the reduced scale shall be graduated on the basis of one-third of an inch to an inch. The large sheet is adjusted so that the left edge 70 of its field is at the left-hand edge of the enlarged scale. I then mark the middle line of the reduced picture and large sheet and cause them both to register exactly with the top edge of the ruler or bar when the latter 75 is in a horizontal position. I then lay off on the small picture with the reduced scale a field corresponding with the field on the large sheet. Now to properly locate the reduced picture I raise the bar until its upper edge 80 corresponds with one of the upper corners of the field of the large sheet. I then slide the reduced picture to the right or left until the corresponding corner of the reduced field is also on the line of the said upper 85 edge of the bar, while the horizontal median lines are maintained in an exact registered position. The reduced picture is then tacked in place. Now I move the reduced scale d² to the left until its left-hand graduation 90 corresponds with the left edge of the field of the small picture. I then place a dot or prick-point f³ on the small picture opposite any assumed point on the reduced scale—as, for instance, opposite the division 16—and locate a similar dot g³ on the large sheet opposite the corresponding division 16 of the large inch-scale. I then move the bar and slide the movable support F until the point f² of the hook rests on the said prick-point and make 95 an index-mark on the said movable support opposite any division of the reduced scale—as,

for instance, the division 11. Now I slide the movable support G along the bar until its paper or card covers the dot g^3 . I dot this point on the card and cut away the card, so as 5 to form a pointed end g^2 , and then adjust the support until this pointed end registers exactly with the dot g^3 . I then make an index-mark on the support to correspond with the division 11 of the large inch-scale, and all is 10 ready for work. Now to lay off any point on the large sheet I simply adjust the card-point f^2 to that particular point on the small picture and note the point where its index-mark meets the reduced scale. I then slide 15 the movable support G until its index-mark registers with the corresponding division of the large scale. The point of the card will designate the corresponding point of the enlarged picture. This point is so shaped that 20 the artist may work in the adjacent portions of the picture. In this way he may very quickly and with great accuracy lay off the entire picture. So, also, he may at any time before his picture is completed prove any one 25 of his points at once. So, also, he may continue from point to point in regular order, or he may skip from place to place, and rely with certainty upon his parts properly matching when they are merged together. I prefer to 30 use paper or card-board on the movable supports because they are clean, white, and convenient. So, also, they are not so harsh as metal or celluloid, &c., and do not rub or mar the sheet or finished work. I would have it 35 understood, however, that I may use any material where I employ the paper, and that all substances are contemplated and covered by my claims. Again, I might employ sets of these cards or pointers of metal or other material and have corresponding sets of cards or 40 pointers F and G; but I prefer to use one small card F and to cut suitable cards G to correspond therewith, as circumstances may require. So, also, the reduced inch-scales might 45 be made in sets to correspond with the usual sizes of small pictures, or the reduced scale may be made at the time to correspond with the requirements of the work in hand, as above explained. The apparatus is obviously 50 adapted equally well to reduce from a large picture to a small one, and this change needs no special elucidation.

A plate or bar D' may be employed and held in place by suitable screws for securing 55 the reduced inch-scales in position. The bar may be of any suitable material, and the frame A also may be of any convenient form. That shown in the drawings I have found to be very desirable, in which the drawing-board 60 or stretching-frame is held in place by set-screws b, and adjusting-screws b' may be employed, if desired, for setting the stretching-frame or drawing-board out, so the planes of the picture and that of the large sheet may 65 coincide with each other.

Instead of the cord and weight, the free end of the bar may be engaged with any suitable device for enabling it to be sustained at any desired position and moved freely from place to place.

The overhanging hooked form of the pointer paper or card is of great convenience, as it enables the artist to work from the top downward and to complete the work all about and below the point before changing the same.

What I claim is—

1. A drawing apparatus for enlarging or reducing pictures, consisting of the combination, with a suitable frame for the drawing-sheet and the copy, of a pivoted bar provided with a large scale, a small scale, and movable supports F G, bearing pointers, said bar being adapted to be traversed across the sheet, and the pointer-supports adapted to be adjusted to corresponding points along their respective scales, substantially as described.

2. A drawing apparatus for enlarging or reducing pictures, consisting of the combination, with a supporting-frame for the drawing-sheet and the copy, of a pivoted bar D, a fixed scale d' , a reduced scale d^2 , and pointers fixed to movable supports adapted to be adjusted along their respective scales, said reduced scale being made interchangeable with other reduced scales to correspond with the dimensions which the reduced picture bears to the larger picture, substantially as described.

3. The combination, with the movable support G, of a pointer made of paper or card-board, substantially as and for the purposes described.

4. The combination, with the movable supports F and G, of pointers made of paper or card-board, substantially as and for the purposes described.

5. The combination, with the bar D, having a permanent inch or other scale d' , of an interchangeable scale d^2 and means for temporarily securing said scale d^2 in place on the bar, substantially as described.

6. The combination, with the movable supports F and G, of the pointers supported therefrom and having overhanging hooked points, thereby leaving a working-space between them and the supports, substantially as described.

7. The combination, with the bar D and movable pointer-supports F G, of means at the free end of said bar for adjusting and supporting the same in any position, substantially as described.

In testimony whereof I sign this specification in the presence of two witnesses.

JULIUS E. ULMER.
